Inventor.

Milton A. Fisk

United States Patent Office.

MILTON A. FISK, OF SPRINGFIELD, MASSACHUSETTS, ASSIGNOR TO EDWARD M. WESSON, OF SAME PLACE.

Letters Patent No. 75,257. dated March 10, 1868.

IMPROVEMENT IN HARNESS-TRIMMINGS.

The Schedule referred to in these Letters Patent and making part of the same.

TO ALL WHOM IT MAY CONCERN:

Be it known that I, MILTON A. FISK, of Springfield, in the county of Hampden, and State of Massachusetts, have made and invented certain new and useful Improvements in the Manufacture of Harness-Trimming; and I do hereby declare the following to be a full, clear, and exact description thereof, reference being had to the annexed drawings, making a part of this specification, in which—

Figure 3 is a plan of the head or trimming, and

Figure 4 a section of the same, showing the insertion of the loop.

In the manufacture of harness-trimmings, sheet brass or other metal is usually employed, from which such trimmings are "struck up" by means of dies, of any desired form or pattern, and the larger varieties strengthened by "filling" the insides thereof with lead or some similar substance.

To the inside of these trimmings is attached, by means of solder, a stem or loop of wire, usually of brass or iron, whereby they are secured to harnesses, and the outside thereof is usually washed or plated with a thin covering of silver, or some white-metal or amalgam, to impart an improved appearance. But such trimmings, being made of thin, light material, that they may the more readily receive the impression of the dies, are easily jammed or indented, and are often entirely detached from the stem or loop by failure of the solder to adhere; and again, the wash or plate soon wears off, when they assume a sullied, tarnished appearance.

My invention, which has the same general appearance as the trimming above described when new, is designed to remedy the defects thereof, that is, to produce a trimming not easily jammed or indented, to which the loop is firmly attached, and which will preserve a clean, white appearance, even after the wash or plate is worn off.

To enable others skilled in the art to practise my invention, I will describe the construction thereof, and my method of proceeding in manufacturing the same.

The head or trimming *a a*, I make of a round or circular form, about one inch and a half in diameter, as seen in fig. 3, the face or outer surface thereof being convex, while the back or inner surface is concave, and provided with slight sockets or projections around and for the support of the loop *c c*, as seen in fig. 4. By this method of construction I obtain great strength and durability without increase of heft or cost. The loop *c c* I construct of ordinary brass or iron wire of a size sufficient for strength, bending the wire a short distance from the head or trimming, nearly at right angles, and the same again near the ends, as seen in fig. 4. But as the head or ornament *a a* is of a thickness and of a metal or amalgam that could not be "struck up" with a die, I cast or run the same in a mould prepared for that purpose, and instead of soldering the loop *c c* to the head or ornament *a a*, I cast or run such head or ornament on to such loop, thus producing the head or ornament *a a*, and attaching thereto the loop *c c* in a firm and secure manner at one and the same operation.

The moulds which I employ are constructed of brass, ordinarily and on nearly the same principle as a common bullet-mould, except that one of the jaws, which open laterally, is constructed to open through the centre thereof horizontally, and provided with two small openings to each matrix to allow the insertion of the loop *c c*. The matrix for the head or ornament is formed on the faces of the jaws of the mould which open laterally, and of any design desired, and the opening for the melted metal or amalgam being on the top or upper side of the moulds, the matrix is so arranged that the melted amalgam, when poured in, strikes the outer edge or circle of the head or ornament *a a* first.

In the preparation of the amalgam used for casting the head or ornament *a a*, I make use of lead, antimony, and tin in the following manner and proportions: I melt eight (8) parts of tin, and raise it to a red heat; I next add twelve (12) parts of antimony, and as soon as the antimony is thoroughly dissolved, I add one hundred (100) parts of lead. When all are melted and thoroughly mixed, the amalgam is then ready for use or casting. And it is a peculiarity of the amalgam prepared as above described, that it will run around the loop *c c*, penetrating and filling every crevice, figure, and interstice of the matrix, thus producing a very superior article of manufacture, and at the same time preserving a very smooth, clean appearance, and I do not know of any other metal or amalgam that will answer the purpose of my invention so well as that herein set forth.

The moulds being properly prepared, I insert the loop *c c* in the openings provided therefor, projecting the

ends of the loop into the matrix sufficiently to allow the melted amalgam to run round them freely. I then pour in the metal or amalgam, and allow the same to cool or harden. I then remove the trimming from the mould, when it is ready for cleaning, and washing or plating with silver in the ordinary manner, if desired.

Trimmings manufactured in the manner herein specified, I consider superior in quality, durability, and appearance to those manufactured in the ordinary manner.

I do not claim to have invented any new amalgam or composition, nor do I claim to have invented any article of manufacture absolutely new in kind and unheard of before.

My invention relates to the improvement of an old manufacture, and consists in the construction of a rosette or harness-trimming of a material and in a manner never before, to my knowledge, employed in such manufacture, the result of which is both a better and cheaper article, constituting an improvement of the trade.

Having thus described my invention and the method of constructing the same, what I claim as new, and for which I desire to obtain Letters Patent, is—

As a new article of manufacture, a rosette or harness-trimming, when constructed as herein described, and for the purpose specified.

January 15, 1868.

MILTON A. FISK.
